UNITED STATES PATENT OFFICE.

DAVIS S. WILLIAMS, OF LOS ANGELES, CALIFORNIA.

JOINTED FIGURE.

1,345,052.

Specification of Letters Patent. Patented June 29, 1920.

Application filed October 27, 1919. Serial No. 333,768.

To all whom it may concern:

Be it known that I, DAVIS S. WILLIAMS, citizen of the United States, residing at Los Angeles, in the county of Los Angeles and 5 State of California, have invented a new and useful Jointed Figure, of which the following is a specification.

My invention relates to toys and more particularly to a type of toy which is formed of 10 several sections susceptible to various relative manipulations for the purpose of changing the appearance of the toy. The object of the invention is to provide a jointed figure in which the sections may be rotated upon 15 each other to any desired degree without destroying the continuity of the surface of the figure. Another object is to provide a jointed figure having a plurality of wedge shaped sections rotatively connected for relative angular adjustment, to change the shape 20 of the body of the figure. Various other objects and advantages will be apparent from the following description of the accompanying drawings which form a part of this disclosure and which illustrate a preferred 25 form of embodiment of the invention.

Of the drawings:

Figure 1 is a side elevation of a figure made in accordance with my invention, 30 showing in dotted lines a second adjustment of the body sections and the hind-leg section.

Fig. 2 is a similar view showing another adjustment.

Fig. 3 is a central longitudinal section 35 showing the pivotal connecting means.

Fig. 4 is a perspective view of one of the wedge shaped body sections.

The figure herein illustrated is in simulation of a bear but it is obvious that it may 40 be a simulation of any other animal or of a fowl, reptile, insect or human figure, either natural or mythical, and may be constructed of wood or other available material.

In the drawings, 1 designates the head terminal section having a flat circular bearing surface 2 adapted to engage with a companion flat circular bearing surface 3 of the fore-leg section 4. The opposite flat circular bearing surface 5 of the section 4 is angled relative to the surface 3 and the lower portion of the section 4 is bifurcated to form fore legs 6-6. The hind-leg section 7 is likewise bifurcated to form hind legs 8-8 and has an angled flat circular bearing surface 9. Intermediate the bearing surfaces 5 and 9 of the two leg sec-

tions there is positioned two circular wedge shaped body sections 10-11 each having opposed flat bearing surfaces 12-13. The several sections are provided with longitudinal orifices positioned coincident to the axes of each bearing surface and are permanently joined together in relative rotative relation by a pivotal connecting element 14 threaded through the aligned orifices. Said element may be of wire, elastic or other suitable material, one end being anchored in a recess in the head section and the opposite end anchored to the hind-leg section, preferably in the crotch of the furcations. From 70 the above it will be understood that by rotating the various sections to relatively different angles the figure may be made to assume a large number of different forms and positions of grotesque and amusing characters, 75 and that such relative turning of the sections will not destroy the continuity of the surface of the figure, this being due to the circular formation of the coöperating bearing surfaces.

Having described my invention I claim:

1. A jointed figure of the class described combining a plurality of sections having coöperating bearing surfaces, and means connecting the sections in relative rotative relation, the coöperating bearing surfaces being of duplicate size and contour to permanently maintain the continuity of the surface of the figure during all rotative adjustment of the several sections. 90

2. A jointed figure of the class described combining a plurality of sections having relatively angled coöperating bearing surfaces, and means connecting the sections in relative rotative relation, the coöperating bearing surfaces being of duplicate size and contour to permanently maintain the continuity of the surface of the figure during all rotative adjustment of the several sections. 95

3. A jointed figure of the class described combining a plurality of sections having circular coöperating bearing surfaces, and means positioned coincident to the axis of the bearing surfaces for connecting the sections in relative rotative relation, the coöperating bearing surfaces being of duplicate size to permanently maintain the continuity of the surface of the figure during all rotative adjustment of the several sections. 100

4. A jointed figure of the class described combining a plurality of sections having rel-

- atively angled circular coöperating bearing surfaces, and means positioned coincident to the axis of said bearing surfaces to connect the sections in relative rotative relation, 5 the coöperating bearing surfaces being of duplicate size to permanently maintain the continuity of the surface of the figure during all rotative adjustment of the several sections.
- 10 5. A jointed figure of the class described combining two opposed terminal sections, a plurality of intermediate sections, and means connecting the sections in relative rotative relation, the sections having coöperating bearing surfaces which are of duplicate size and contour to permanently maintain the continuity of the surface of the figure during all rotative adjustment of the several sections.
- 15 6. A jointed figure of the class described combining two opposed terminal sections each provided with circular bearing surfaces, a plurality of intermediate sections each having circular bearing surfaces for 20 coöperation with the bearing surfaces of the
- adjacent sections, and means positioned coincident to the axis of the bearing surfaces for connecting the sections in relative rotative relation, the coöperating bearing surfaces being of duplicate size to permanently 30 maintain the continuity of the surface of the figure during all rotative adjustment of the several sections.
7. A jointed figure of the class described having a body formed of a plurality of circular wedge shaped sections, and a pivotal connecting element positioned coincident to the axes of said sections, the sections having coöperating bearing surfaces of duplicate size and contour to permanently maintain the continuity of the surface of the body during all rotative adjustments of the sections. 35

Signed at Los Angeles, California, this 20th day of October, 1919.

DAVIS S. WILLIAMS.
